Patented May 1, 1917.

Inventor:
Salathiel S. Adams.

UNITED STATES PATENT OFFICE.

SALATHIEL S. ADAMS, OF LAFAYETTE, TENNESSEE.

DESIGN FOR A TIRE-TREAD.

50,673.

Specification for Design.

Patented May 1, 1917.

Application filed March 3, 1917. Serial No. 152,410. Term of patent 7 years.

To all whom it may concern:

Be it known that I, SALATHIEL S. ADAMS, a citizen of the United States, residing at Lafayette, Route No. 4, in the county of Macon and State of Tennessee, have invented a new, original, and ornamental Design for a Tire-Tread, of which the following is a specification, reference being had to the accompanying drawing, forming part thereof.

The figure is a perspective view of a portion of tire tread showing my new design.

I claim:

The ornamental design for a tire tread as shown.

SALATHIEL S. ADAMS.

Witnesses:

B. H. O. BENNON,
B. J. DRIVER.
